UNITED STATES PATENT OFFICE.

FRANK A. SYLVESTER, OF MACON, GEORGIA.

ADVERTISING DEVICE.

1,424,323.

Specification of Letters Patent. Patented Aug. 1, 1922.

Application filed February 25, 1922. Serial No. 539,263.

To all whom it may concern:

Be it known that I, FRANK A. SYLVESTER, a citizen of the United States of America, residing at Macon, in the county of Bibb 5 and State of Georgia, have invented certain new and useful Improvements in Advertising Devices; and I do hereby declare that the following is a full, clear, concise, and exact description of the invention, such as 10 will enable others skilled in the art to which it appertains to make and use the same.

The present invention relates to advertising devices and more particularly to an outdoor display sign adapted to be placed adjacent a highway preferably travelled by 15 automobiles so that the goods of merchants or others may be advertised to automobilists when travelling over the highway approaching the city or village inhabited by the 20 advertiser.

The purpose of the present invention is to provide a movable sign of a fanciful form and more especially in the design of a weather vane which is attractive in appearance, strong and efficient in use and which 25 is comparatively inexpensive to manufacture thereby rendering the same commercially desirable.

A further object of the present invention 30 is to provide an advertising device representing a weather vane having the wind wheel thereof comprising an ordinary automobile wheel in which is arranged a wind propelling blade thereby making the sign attractive to the observer.

With the above and other objects in view, the invention consists of the novel features of construction, formation and arrangement of parts as will be more fully described and 40 pointed out in the appended claims.

In the accompanying drawings, I have shown a simple and improved form of the invention, but it is to be understood that the construction shown is capable of considerable modification and such modification as 45 is within the scope of my invention, I consider within the spirit thereof.

In these drawings:

Figure 1 is a side elevation of the advertising device comprising the present invention;

Figure 2 is a front elevation of the same;

Figure 3 is a vertical section through the wind wheel thereof; and,

Figure 4 is a similar view showing a slightly modified form.

Referring now more particularly to the drawings, wherein the various parts are designated by like and corresponding reference characters throughout the several views, the numeral 1 indicates a post or other suitable support adapted to be placed adjacent a highway. Arranged on each side of this post 1 are suitable plates 2 which may contain advertising matter. Secured to the upper 60 end of the post 1 by means of a bolt 3 is a bracket 4 which latter forms a bearing support for an arm 5 of the vane. Formed with one end of the this arm 5 is a plate 6 having the configuration of the feather end of an 65 arrow and suitable advertising matter may be placed on the opposite faces of this plate. Rotatably connected to the opposite end of the arm 5 is a wind wheel 7 which preferably has the configuration of an ordinary automobile wheel and when desired, it may have 70 suitable advertising matter placed thereon which would be attractive to the observer.

The rod 5 is provided with a large ball-shaped portion 8 which is adapted to be 80 seated in a socket 9 formed in the upper end of the bracket 4 and extending from this ball 8 is a pin 10 which is also seated in the recess formed in the bracket 4. This ball 8 and pin 10 form the perpendicular axis for 85 the weather vane and the wind wheel as well as the plate 6 are properly balanced upon the rod 5 so that they may turn upon their perpendicular axis and the wind wheel 90 7 will turn with the blowing of the wind. 90

A suitable bearing 11 is placed upon the rod 5 upon which is adapted to freely rotate the automobile wheel as shown. This automobile wheel consists of the tire casing 12, the rim 13, the spokes 14 and the hub 95 15, all of which are of the usual and well known construction.

This automobile wheel is turned into a wind wheel by the application of the propelling blades 16 thereto. The propelling 100 blades are provided with the hub portions 17 which are adapted to fit over the hub 15 of the automobile wheel and the blades 16 are arranged between the spokes 14 of the wheel. A disk plate 18 is secured to the outer end of the bar 5 by means of the hub 19 so that the blade 16 will be retained in position within the spokes of the automobile wheel and the latter fastened upon the bearing 11. These blades 16 being relatively wide will catch the wind as it blows 105 and cause the automobile wheel to revolve. 110

In the slightly modified form of the invention shown in Figure 4, I have illustrated a wind wheel having the configuration of an automobile wheel but which is preferably made of sheet metal. This form of wind wheel comprises an outer casing 20 which is of the configuration of an ordinary tire casing and has connected thereto, the outer ends of the radially extending 10 spokes 21. The inner ends of these spokes 21 are secured to the hub 22 and secured to each spoke is a propelling blade 23. The hub may be rotatably mounted upon the bearing 24 carried by the rod 5 and retained 15 in place by the disk 18.

Owing to the attractive appearance of the wind wheel, the advertising matter upon the plates 2, vane 6 or that which may be placed upon the tire of the wind wheel will be 20 readily noticed by persons passing the device.

I claim:

1. An advertising device having the configuration of a weather vane in which is included a wind wheel, said wind wheel comprising an ordinary automobile wheel and tire casing therefor, propelling blades, a hub for said propelling blades, the hub of said propelling blades adapted to be inserted 25 over the hub of the automobile wheel, and means for connecting said hubs together.

2. An advertising device of the character described comprising a support, a bracket arranged upon said support, an arm 35 rotatably connected to said bracket, a vane carried by one end of said arm, a bearing carried by the opposite end of said arm, a wind wheel, said wind wheel comprising an

ordinary automobile wheel arranged upon said bearing, propelling blades arranged 40 within said automobile wheel and a disk for retaining said propelling blades and automobile wheel upon said bearing.

3. An advertising device comprising a supporting post, a bearing secured to the upper end of said post, a vane rod, a ball and socket connected between said vane rod and said bracket whereby the vane rod may rotate thereupon, a wind wheel journaled upon said vane rod, said wind wheel comprising a hub, spokes radiating from said hub, a casing supported by the outer ends of said spokes, and blades detachably arranged between the spokes of said wheel substantially as and for the purpose specified.

4. An advertising device of the character described comprising a support, a bracket secured to the upper end of said support, an arm pivotally and detachably connected 60 to said bracket, a vane carried by one end of said arm, a bearing formed with the opposite end of said arm, a wheel journaled on said bearing, said wheel comprising a hub portion, spokes radially extending from 65 said hub portion, a rim connected to the outer ends of said spokes, propelling blades arranged between said spokes and extending between the hub and rim portions of the wheel, and means connected to said rod 70 for retaining said wheel and propelling blades thereupon substantially as and for the purpose specified.

In witness whereof I have hereunto set my hand.

FRANK A. SYLVESTER.
